UNITED STATES PATENT OFFICE.

NILS FREDERICK AMBURSEN, OF BROOKLINE, MASSACHUSETTS, ASSIGNOR TO AMBURSEN COMPANY, OF BOSTON, MASSACHUSETTS, A CORPORATION OF NEW JERSEY.

NOZZLE.

1,124,579.

Specification of Letters Patent. Patented Jan. 12, 1915.

Application filed February 28, 1913. Serial No. 751,201.

To all whom it may concern:

Be it known that I, NILS FREDERICK AMBURSEN, a citizen of the United States, and a resident of Brookline, in the county of 5 Norfolk and State of Massachusetts, have invented a new and useful Improvement in Nozzles, of which the following is a specification.

My invention relates to nozzles for receiving and mixing dry comminuted material with liquid and discharging such mixture under pressure, and more especially to nozzles for cement guns, so called, or devices for forcibly projecting cement-mortar 15 and the like, as described in United States Letters Patent to C. E. Akeley, 984,254, granted February 14, 1911.

The object of my invention is to improve and simplify the construction and increase the efficiency of such nozzles in the manner hereinafter set forth.

Heretofore, so far as I am aware, it has been necessary to force the liquid into nozzles of the kind to which the present application relates, under pressure, and to apply the same to the exterior of the stream of dry comminuted material. By means of the present invention it is not necessary to employ liquid under pressure, although 30 it may be so employed if desired, and the liquid is injected directly into the interior of the stream of dry comminuted material, thereby insuring greater uniformity of mixture than when it is applied to the exterior 35 thereof.

Two embodiments of my invention are shown in the drawings which accompany and form a part of this application.

In the drawings, Figure 1 is a longitudinal section of my improved nozzle. Fig. 2 is a section taken on the line 2—2 of Fig. 1, and Fig. 3 is a fragmentary section on an enlarged scale. Fig. 4 is an end view on a smaller scale of a modified partition, and 45 Fig. 5 is a section taken on the line 5—5 of Fig. 4.

In the particular drawings selected for illustrating the principle of my invention, 1 represents a sleeve having its forward 50 portion outwardly flaring to form an expansion chamber 1', hereinafter more fully referred to, and its rearward portion adapted to be secured by threads or other suitable means to the hose 2 for conveying dry comminuted material under pressure to the nozzle. In the present instance the screws 3 are employed to secure the union between the sleeve and hose. Extending across the expansion chamber 1' formed by the enlarged forward portion of the sleeve is the 55 partition 4, shown herein as rearwardly tapering and as secured to the sleeve by the screw 5 and the threaded end of the liquid inlet pipe 8 which, as indicated in Fig. 1, is of much smaller diameter than 60 the hose 2. The partition in the present instance is provided with a duct 6 communicating with, and as shown forming a direct extension or continuation of, the liquid inlet pipe 8, said duct and pipe having substantially the same diameter. The duct 65 communicates also with an outlet located in the forward edge of the partition about midway between the ends thereof, so that it is approximately in the center of the expansion chamber. In the present instance the outlet consists of the forwardly-projecting pipe 7 screwed into the forward edge of the partition and provided with orifices 7' 7'', preferably divergent, said outlet pipe 70 also being of much smaller internal diameter than the hose 2 and the combined cross-sectional areas of said orifices being 75 preferably not larger than the cross-sectional area of said outlet, as indicated in Fig. 3.

The usual soft rubber liner 9 is provided to line the interior of the expansion chamber 1' formed as aforesaid by the forward portion of the sleeve 1, and a suitably-shaped discharge nozzle 10, also of soft rubber, is held in alignment with the liner 9 by means of the shouldered nut 12, which compresses the flanges of the liner 9 and discharge nozzle 10 against the outer face of 90 the sleeve. In the present instance the discharge nozzle is shown as tapering forwardly from the expansion chamber to a point at a short distance from the end of the nozzle, beyond which the nozzle is cylindrical. The shape of the nozzle causes it to act as a compression chamber for compacting the material after it has expanded and has been mixed with the liquid in the expansion chamber. The partition 4 preferably 95 is coated with soft rubber 13 in order 100 to prevent the nozzle from being damaged by the material.

to prevent abrasion by the comminuted material.

In operation, the hose 2 is connected to any of the usual types of apparatus for forcing therethrough by compressed air dry comminuted material such as cement or lime, sand, and the like, which after admixture with water, form cement mortar or whatever plastic compound is desired to be delivered. In this connection it will be understood that while my improved nozzle is intended to be employed with the device now known as the cement gun, nevertheless it is not limited to such use, inasmuch as it may be employed in connection with comminuted material other than lime, or cement and sand.

When the stream of dry comminuted material, which in the present instance will be assumed to be cement and sand in the proper proportions, impinges against the rearward edge of the partition 4, approximately at, or immediately after, its entrance into the expansion chamber 1', it will be divided into two streams which pass on either side of said partition and which, being under pressure, fill the expansion chamber except immediately in front of the outlet pipe 7 where there will be a clear space. Into this space by means of the outlet pipe 7, liquid such as water is sprayed through the orifices 7' 7", such liquid being injected directly into the interior of the stream of material. As the stream of material is passing the partition and outlet pipes at a high rate of speed, it will create sufficient suction to force the liquid through the pipe 8, duct 6 and outlet pipe 7, so that it is unnecessary to force the liquid into the nozzle under pressure as has heretofore been required, although of course it will be understood that liquid under pressure may be employed, such for example as water under the usual pressure of a water-works delivery main.

When the mixture of comminuted material and liquid passes from the expansion chamber to the compression chamber, it is compacted preparatory to being ejected from the cylindrical end of the nozzle, and during the process of compacting, the liquid passes from the central to the outer portion of the stream of material and thus permeates the entire mass, so that the mixture as finally ejected will have the desired degree of plasticity.

In Figs. 4 and 5, the partition 4' has its rearward edge twisted somewhat in the manner of a propeller blade and extending diagonally across the expansion chamber, while its forward edge, as in Fig. 1, extends diametrically across the same. The stream of dry comminuted material striking the upper and lower portions 14, 14' of the partition will be divided as before into two parts and each part will be given a whirling

or rotary motion, so that after the water has been injected into the interior of the stream as above described, and the plastic mass compacted by the compression chamber, it will leave the nozzle as a whirling spray and will be distributed over a larger surface area. This is advantageous for laying on the finishing coat of cement-mortar or the like.

While I have specifically described two particular embodiments of my improvement, it will be understood that various modifications may be made therein by those skilled in the art, without departing from the principle of my invention.

I claim:

1. The combination with a hose for conveying dry comminuted material under pressure and a pipe for conveying liquid of a nozzle connected to said hose for receiving dry comminuted material, mixing the same with liquid and discharging such mixture under pressure, said nozzle having means extending across the same for dividing the stream of dry comminuted material, and means communicating with said pipe for injecting liquid directly into the interior of said stream of dry comminuted material after the same has been divided.

2. The combination with a hose for conveying dry comminuted material under pressure and a pipe for conveying liquid of a nozzle connected to said hose for receiving dry comminuted material, mixing the same with liquid and discharging such mixture under pressure, said nozzle having means for dividing the stream of dry comminuted material and means communicating with said pipe for injecting liquid directly into the interior of the stream of dry comminuted material after the same has been divided.

3. The combination with a hose for conveying dry comminuted material under pressure and a pipe for conveying liquid of a nozzle connected to said hose for receiving dry comminuted material, mixing the same with liquid and discharging such mixture under pressure, said nozzle having means extending across the same for dividing the stream of dry comminuted material, and means communicating with said pipe for spraying liquid directly into the interior of said stream of dry comminuted material after the same has been divided.

4. The combination with a hose for conveying dry comminuted material under pressure and a pipe for conveying liquid of a nozzle connected to said hose for receiving dry comminuted material, mixing the same with liquid and discharging such mixture under pressure, said nozzle having means for dividing the stream of dry comminuted material and means communicating with said pipe for spraying liquid directly into the interior of said stream of dry comminuted material after the same has been divided.

interior of the stream of dry comminuted material after the same has been divided.

5. The combination with a hose for conveying dry comminuted material under pressure of a nozzle connected to said hose for receiving dry comminuted material, mixing the same with liquid and discharging such mixture under pressure, a partition extending across said nozzle, said partition being provided with a duct for liquid and with an outlet communicating with said duct, said outlet being located in the forward edge of said partition and about midway between the ends thereof for injecting liquid directly into the interior of the stream of dry comminuted material after the same has been divided by said partition, and a liquid inlet pipe communicating with said duct.

6. The combination with a hose for conveying dry comminuted material under pressure of a nozzle connected to said hose for receiving dry comminuted material, mixing the same with liquid and discharging such mixture under pressure, a rearwardly-tapering partition extending across said nozzle, said partition being provided with a duct for liquid and with an outlet communicating with said duct, said outlet being located in the forward edge of said partition and about midway between the ends thereof for injecting liquid directly into the interior of the stream of dry comminuted material after the same has been divided by said partition, and a liquid inlet pipe communicating with said duct.

7. The combination with a hose for conveying dry comminuted material under pressure and a pipe for conveying liquid of a nozzle connected to said hose for receiving dry comminuted material, mixing the same with liquid and discharging such mixture under pressure, said nozzle having an expansion chamber, means extending across said expansion chamber for dividing the stream of dry comminuted material immediately after its entrance into said expansion chamber, and means communicating with said pipe for injecting liquid directly into the interior of said stream of dry comminuted material after the same has been divided.

8. The combination with a hose for conveying dry comminuted material under pressure and a pipe for conveying liquid of a nozzle connected to said hose for receiving dry comminuted material, mixing the same with liquid and discharging such mixture under pressure, said nozzle having an expansion chamber, means extending across said expansion chamber for dividing the stream of dry comminuted material immediately after its entrance into said expansion chamber, means communicating with said pipe for injecting liquid directly into the interior of said stream of dry comminuted

material after the same has been divided, and a compression chamber located forwardly of said expansion chamber.

9. The combination with a hose for conveying dry comminuted material under pressure of a nozzle connected to said hose for receiving dry comminuted material, mixing the same with liquid and discharging such mixture under pressure, said nozzle having an expansion chamber, a partition extending across said expansion chamber for dividing the stream of dry comminuted material, said partition being provided with a duct for liquid with an outlet communicating with said duct for injecting liquid directly into the interior of the stream of dry comminuted material after the same has been divided by said partition, and a liquid outlet pipe communicating with said duct.

10. The combination with a hose for conveying dry comminuted material under pressure of a nozzle connected to said hose for receiving dry comminuted material, mixing the same with liquid and discharging such mixture under pressure, said nozzle having an expansion chamber, a rearwardly-tapering partition extending across said expansion chamber for dividing the stream of dry comminuted material, said partition being provided with a duct for liquid and with an outlet communicating with said duct for injecting liquid directly into the interior of the stream of dry comminuted material after the same has been divided by said partition, and a liquid inlet pipe communicating with said duct.

11. The combination with a hose for conveying dry comminuted material under pressure of a nozzle connected to said hose for receiving dry comminuted material, mixing the same with liquid and discharging such mixture under pressure, said nozzle having an expansion chamber, a partition extending across said expansion chamber for dividing the stream of dry comminuted material, said partition being provided with a duct for liquid and with an outlet communicating with said duct for injecting liquid directly into the interior of the stream of dry comminuted material after the same has been divided by said partition, a liquid inlet pipe communicating with said duct, and a compression chamber located forwardly of said expansion chamber.

12. The combination with a hose for conveying dry comminuted material under pressure of a nozzle connected to said hose for receiving dry comminuted material, mixing the same with liquid and discharging said mixture under pressure, a partition having its rearward edge extending diagonally and its forward edge diametrically, across the nozzle, said partition being provided with a duct for liquid and with an outlet communicating with said duct, said

4
outlet being located in the forward edge of said partition and about midway between the ends thereof, and a liquid inlet pipe communicating with said duct for conveying liquid to said material.

5 13. The combination with a hose for conveying dry comminuted material under pressure of a nozzle connected to said hose for receiving dry comminuted material, 10 mixing the same with liquid and discharging said mixture under pressure, an expansion chamber, a partition having its rearward edge extending diagonally, and its forward edge diametrically, across said expansion chamber, said partition being provided with a duct for liquid and with an outlet communicating with said duct, and a liquid inlet pipe communicating with said duct for conveying liquid to said material.

15 14. A cement-gun nozzle comprising in combination a transverse partition, substan-

25 tially rectangular in longitudinal section, said partition being provided with a duct for liquid and with an outlet communicating with said duct, said outlet being located in the forward edge of said partition and about midway between the ends thereof for injecting liquid directly into the interior of the stream of dry comminuted material after the same has been divided by said partition, and a liquid inlet pipe communicating with said duct, the cross-sectional area of said outlet being much smaller than that of the nozzle inlet.

30

35 In testimony whereof, I have hereunto subscribed my name this 27th day of Feb. 1913.
